Application December 16, 1949, Serial No. 133,354

2 Claims. (CL. 321—2)

1

The present invention relates to improvements in high voltage power supply systems for television receivers. There are four types of supply systems in general use:

First, that which is based on step-up transformation and rectification of the 60 cycle alternating current supply, and modified forms involving the use of voltage multipliers, as described at pages 158-164, Grob, Basic Television, Principles and Servicing, McGraw-Hill Book Company, Inc., New York, 1949;

Second, the R. F. type, wherein a rectifier is energized by a high-frequency oscillator, as described in the article entitled "Television High Voltage R. F. Supplies" by Mautner and Schade, RCA Review, March 1947, vol. VIII, No. 1, pp. 43-81, R. C. A. Laboratories Division, Princeton, New Jersey, and also at pp. 164-168 of the above-cited book by Grob;

Third, the fly-back type, wherein energy is obtained by rectification from the inductive circuit provided for horizontal scanning, as described at pages 168-170 of Grob's book and in U. S. Patent No. 2,051,372 to Farnsworth, No. 2,265,620 to Bahring, No. 2,074,495 to Vance, and No. 2,218,764 to Moller and Bahring;

Fourth, the pulse-type, as described in the article entitled "Pulse-Type High-Voltage Supply," Siezen and Kerkhof, Proceedings of the Institute of Radio Engineers, March 1948, pp. 401-407.

The advantages, disadvantages, and limitations of the various types of television receiver power supply systems are known to the art and are discussed in the literature, particularly in the patents and publications cited above. Among the primary desirable attributes of a power supply system are: (1) A high voltage D. C. output, which ranges from as low as two kilovolts for some types of directly viewed tubes to 30 kilovolts or higher for projection tubes; (2) low average current output, ranging from 100 to 200 microamperes; (3) light weight; (4) small size; (5) minimum shock hazard; (6) good power efficiency; (7) minimum nonsynchronous R. F. interference; (8) inexpensive filtering circuits.

These requirements often dictate the use of a pulse-type power supply in specific designs, most frequently in projection type receivers. Constant pressure has been on those working in the art to obtain a higher voltage output per unit weight, and gradual progress has been made along that line. The present invention provides an improvement whereby the voltage output and power efficiency of the pulse-type power supply are radically increased.

The conventional pulse-type power supply is based on the periodic interruption of a current

2

flowing in an inductive circuit. The current builds up a magnetic field which suddenly collapses when the current flow is interrupted and the high voltage of the transient oscillation induced by this reaction is rectified and filtered. Each interruption of current flow is followed by a train of damped oscillations which occur during dissipation of energy and substantially complete collapse of the stored power. Then the magnetic field is completely built up again and the cycle is repeated. Further, only the peaks of the first cycle of the damped transient oscillation are rectified and the available high voltage current is low since the total time during which peaks occur is small by comparison to the time of each series of damped oscillations. The primary object of the present invention is to effect a radical increase in efficiency by maintaining most of the magnetic energy within the system and decreasing the number of useless cycles of the periodically recurring oscillations.

In accordance with the invention the natural frequency of the transformer circuit is so related to the repetition rate of the interruptions of current in the transformer circuit and to the time during which the power tube is conducting that the time for one or only a few complete cycles of the fundamental frequency of the transformer output voltage plus the time of each increment of current required to reach peak current in the plate inductance, is equal to the reciprocal of the driving pulse frequency.

A pulse-type power supply in accordance with the invention comprises an energy source, an inductance which is periodically charged by that source, means including a switching tube for periodically interrupting the flow of current in said inductance, thereby causing the magnetic field to collapse, whereby there appears across said inductance an oscillatory voltage, means for peak-rectifying said voltage to derive a unidirectional voltage, and capacitance effectively in parallel with said inductance to form a circuit having such a resonance characteristic that the periodically recurring applied increments of current in said inductance are initiated at times when the oscillatory current in the last-mentioned circuit is near or at its peak value and of the same polarity as those increments.

I prefer that the distributed capacitance of an inductor be utilized as the above-mentioned parallel capacitance. The frequencies involved are such that economies may be effected in this manner, dispensing with the provision of a separate capacitor.

The explanation of the basic concept of the invention may be simplified by drawing an

analogy between the conventional pulse-type power supply and the pendulum. The pendulous weight has its maximum kinetic energy at the mid-point of its swing. The inductance has its maximum energy at the end of its charge. The flow of current into the inductance is terminated at that instant. It may be assumed, to continue the analogy, that the manual operator of the pendulum stops his "push" at the mid-point of its swing. It is well known that, due to losses, the energy of a pendulum will decrease to zero if push is applied and no second push occurs until its oscillatory swing decreases in amplitude to zero. In such cases, the kinetic energy of the pendulous system must be entirely built up again in order to attain the maximum swing again. In the conventional type of pulse-type power supply, the natural periodicity of the inductor circuit (corresponding to the pendulum) and the repetition rate of the driving impulses (each corresponding to a push ceasing at the mid-point of swing after a previous cycle of natural oscillations has ceased) are such that the part of the originally stored magnetic energy which is left after the first cycle, i. e., which is not used for the high-voltage rectification, is completely dissipated between driving impulses.

Only the peak voltage portions of the first oscillation are rectified and the following amplitudes, decreasing in accordance with a logarithmic decrement, of the many succeeding oscillations in each train, are such that these succeeding oscillations do not attain the threshold of rectification. The useless oscillations comprise by far the greater portion of the total number of oscillations in each train. Magnetic energy is dissipated to the point of exhaustion during the time of these useless oscillations. The ratio of available high-voltage power to stored magnetic energy is accordingly low.

I have found that the above-mentioned ratio and the power efficiency of a pulse-type power supply may be radically increased by applying power to the inductance at a repetition rate which is comparable to the natural frequency of the inductive circuit, or by so predetermining the natural frequency that it is comparable to the impulse rate. In my novel power supply, the number of oscillations between successive impulses is not a substantial multiple of the number of applied impulses. In the prior art power supply, the number of useless power-dissipating oscillations is many times greater than the number of applied pulses.

Continuing the analogy, my improved power supply may be likened to a pendulum in which an impulse is supplied in the correct phase at the mid-point of each swing, or perhaps every second or third swing. The prior art system may be likened to a pendulum which uselessly swings many times and comes to rest before a new impulse is applied. The analogy was drawn a posteriori for the purpose of explaining the operation of the invention and not a priori.

For a better understanding of the present invention, together with other and further objects, advantages, and capabilities thereof, reference is made to the following description of the accompanying drawings,

Fig. 1 of which illustrates in schematic form a pulse-type power supply system in accordance with the invention; and

Fig. 2 comprising a set of curves employed as an aid in describing the invention.

The symbols employed in the schematic diagram of Fig. 1 are those which are applicable to a

known prior art type of power supply as well as to the present invention. This known type of power supply comprises a sawtooth signal generator, a power amplifier 14 for converting the sawtooth voltage signals into periodically recurring sawtooth currents, an inductance 12 through which these currents flow, and an energy source 11, included in series with the inductance 12 in the plate circuit of the power tube 14 for furnishing the energy represented by these currents. In the prior art circuit the tube 14 functions as a switching tube and periodically closes or becomes non-conductive in order to interrupt the flow of current in inductor 12. Each interruption occurs at the peak of a sawtooth wave of current in inductor 12 and at a time when the magnetic energy stored in its magnetic field is at a maximum. Each interruption of current in inductance 12 causes a transient oscillatory voltage to appear across the inductance. It is the practice to rectify the first peak of this transient voltage, although in those prior art circuits which employ voltage multipliers the first positive and the first negative peaks are in effect rectified. In either case, each train of transient oscillations continues after rectification has occurred. During the continued oscillation following peak rectification, the residual energy of the system is dissipated until it attains a value close to zero. The invention, although it may be represented by the same symbols as the prior art power supply, operates on a distinct principle in that a very substantial amount of stored energy is retained in the system between control signals. In the prior art system substantially all of the energy is dissipated following the termination of each controlling sawtooth signal and before the beginning of the next controlling sawtooth signal. In a power supply in accordance with the present invention, on the other hand, a substantial amount of energy remains in the system after the first control pulse has performed its function and at the instant when the second control pulse becomes effective. In the prior art system the power amplifier tube remains conductive, in response to each sawtooth control signal, sufficiently long to cause the current in the inductance 12 to build up from zero to its peak value. In the system provided by the invention, on the other hand, the intervals of conductivity of the power amplifier tube are relatively very short because it remains open during each interval only sufficiently long to furnish an increment of current from a substantial value (representative of the energy retained in the system) to a peak value.

In the new system provided by the invention, appropriate control pulses as represented by curve Y, Fig. 2, are employed to govern the operation of amplifier tube 14. These control pulses are produced by a pulse generator 16 (shown only in block form), such as a plate-coupled multivibrator. The control pulses could also be produced by a pulse shaping network coupled to a line or horizontal synchronizing system of the television receiver. Since such expedients as signal generators, pulse shaping networks and horizontal synchronizing systems are well known in the art, they need not be described in detail herein. It will be understood that the portion of the control pulse (curve Y, Fig. 2) during the interval t_2-t_3 is of negative polarity and is below the plate current cut-off potential, rendering tube 14 non-conductive, and that the portion of each pulse during the interval t_3-t_4 , for example, is

above cut-off and renders tube 14 conductive. It will be seen from the following description and from what has already been mentioned that the intervals of conductivity of tube 14 in my system are relatively very short.

The control pulses are applied to the control electrode of tube 14 through a suitable coupling network comprising capacitor 17 and grid resistor 18. The cathode of tube 14 is grounded as shown. It will be understood that inductance 12 is shunted by a number of capacitance parameters including its own distributed capacitance and the capacitance of the auto-transformer secondary circuit as reflected back to the primary. These parameters are collectively indicated by the reference numeral 19. In accordance with the invention the parameters of inductance 12 and capacitance 19 are so determined that the magnetic energy in the system is not completely dissipated between successive increments of current in inductance 12.

Each interruption of current in inductance 12 causes a transient oscillatory voltage to appear across the inductance (curve Z, Fig. 2). The peak of this voltage is stepped up by an auto-transformer, the primary of which comprises inductance 12 and the secondary of which comprises series winding portions 12 and 20, wound on the same core. Across the secondary is connected the series combination of a diode rectifier tube 21 and load 22 (generally the accelerating anode circuit of a cathode-ray picture tube, not shown). Across the load is a shunt filter capacitor 23. The filament 24 of diode 21 is provided with its own secondary winding 25 inductively coupled to the auto-transformer. The positive peak of the transient oscillatory voltage is rectified by tube 21.

The rectifier circuit per se, that is, the elements 20, 21, 25, 23, and 22, are individually and collectively a part of the prior art.

Coming now to describe the operation of my improved pulse type power supply, it will be assumed that tube 14 becomes conductive at time t_1 . As shown in curve X of Fig. 2, the plate current in tube 11 instantly assumes a substantial value I_1 . During the interval of conductivity of tube 14, the current supplied to the inductor by the tube increases along a sawtooth characteristic (curve X, Fig. 2), finally attaining a maximum value I_2 , and additional energy is stored in the magnetic field of inductance 12 over and above that which it possesses at instant t_1 . The maximum current value is attained at instant t_2 . At that instant the control pulse applied to the grid of tube 14 (curve Y, Fig. 2) falls to a substantial negative value, cutting off the anode circuit of tube 14 and interrupting the flow of current from source 11 to inductance 12. It is of particular importance to note that the current in tube 14 does not rise from zero value at time t_1 with a sawtooth characteristic, but on the contrary is rapidly initiated at a value I_1 (curve X, Fig. 2). This means that the time of conductivity of tube 14 is short relative to the time which would be required to attain value I_2 , with a sawtooth characteristic initiated at zero value. Since the time of conductivity of tube 14 is a measure of the power efficiency of the system, it will be seen that the invention radically improves power efficiency, the area BCDE in curve W, Fig. 2, representing the power applied during each period of conductivity of tube 14, being much smaller than the area ADE, which is representative of applied power in prior art circuits, the

area ABC being entirely dispensed with in the practice of the invention.

At time t_2 , the plate current of tube 14 drops to zero, and the current through inductor 12 and the magnetic field begin to decrease in value, along a sinusoidal characteristic determined by the natural resonant frequency of the oscillatory circuit comprising inductance 12 and capacitor 19, this decrease being the first stage of a transient oscillation. At time t_3 the current through the inductance and the magnetic field reach instantaneous values of zero (curve W) but attain their maximum rates of change. At time t_4 the energy in circuit 12, 19 is stored in the electrostatic field and the voltage across tube 14 (curve Z) reaches its maximum in a positive direction. The peak of this voltage is rectified by tube 21.

In the prior-art type of power supply, the transient oscillations of the type shown in curves W and Z (following t_2 or power tube cut-off) are allowed to continue until all energy is dissipated from the system. It is within the teachings of the present invention to render tube 14 conductive again at or about time t_4 when the energy from the electrostatic system has again been converted into magnetic energy—i. e., at or near the end of the first cycle of free oscillation in the oscillatory circuit 12, 19. However, the natural frequency of the oscillatory circuit must then approximate the repetition rate of the control pulses, and the output voltage for a given pulse repetition rate is smaller than is the case when the natural frequency is larger. The smaller output voltage requires a higher step-up ratio in the auto-transformer. I prefer to reduce this step-up ratio by rendering tube 14 conductive again at time t_5 —i. e., at or near the end of the second cycle of free oscillation. At instant t_5 a substantial current is flowing in the inductance 12. This current is representative of magnetic energy retained within the system and not lost. As soon as tube 14 becomes conductive, at instant t_6 , this current flows through the anode-cathode circuit of the tube. The current through the inductance is again increased between instants t_5 and t_6 , and input energy is supplied by the tube during this interval. The cycle is then repeated, preferably, as indicated above, at horizontal line frequency.

Thus it will be seen that the invention provides a pulse-type power supply comprising an energy source 11 (which may be the usual low voltage plate supply source of a television receiver), an inductance 12 which is periodically charged by that source (the expression "charged" being employed to designate the development of sawtooth currents), means including a switching tube 14 for periodically interrupting the flow of current in the inductance, thereby causing the magnetic field to begin to collapse (between times t_2 and t_3 , whereby there appears across said inductance an oscillatory voltage (first peak in curve Z), means 21 for peak-rectifying said voltage (at instant t_4) to derive a unidirectional voltage, and a capacitance (which may be the distributed capacitance 19) effectively in parallel with said inductance 12 to form a circuit having such a resonance characteristic that the periodically recurring applied increases of current in said inductance are initiated at times (t_1 and t_6 , curves X and W) when the oscillatory current (curve W) in the last-mentioned circuit is near its peak value and of the same polarity as those increases. It will be seen that at times t_1 and t_6 , the oscillatory current in this resonant circuit

is at or near its peak value. It will also be seen that this oscillatory current is of positive polarity at instants t_2 and t_6 , and that the applied increases of current represented by the curve X, Fig. 2, are of positive polarity. The invention provides a system in which the natural frequency of the oscillatory circuit 12, 19 is such that the time for two complete cycles (t_2-t_6) of the fundamental frequency of the transformer output voltage plus the time required to build up maximum current in the plate inductance (t_6-t_7) is equal to the reciprocal of the driving pulse frequency (i.e., t_7 minus t_2 , curve Y), or

where F is the frequency of the pulses Y.

It will be understood that tube 14 becomes conductive when the leading slope portion of each pulse (curve Y) exceeds the cut-off bias value. As stated above, circuits for producing pulses of this character are well known to those skilled in the art and need not be described in detail herein.

It is desirable to control the duration of the pulses represented by curve Y by adjustment of the pulse generator, in order to correlate the pulse repetition rate and natural frequency of the oscillatory circuit 12, 19. In the specific example shown, the time for two complete cycles of the resonant frequency plus the time necessary to drive the plate inductance to maximum current value is equal to the reciprocal of the driving pulse frequency. It is within the spirit of the invention to make one or two or three or a few complete cycles of the resonant frequency plus the time necessary to drive the plate inductance to maximum current value equal to the reciprocal of the line frequency, because the invention achieves useful results in minimizing the dissipation of magnetic energy from the system between control impulses. The invention becomes particularly useful from the standpoint of increasing power efficiency most economically when free oscillation of the resonant system for two oscillations is permitted, as in the specific illustrative embodiment herein described in detail.

It is particularly important to note that at instant t_4 , the end of the first cycle of the transient oscillation, a substantial amount of current of positive polarity is flowing in inductor 12 (curve W, Fig. 2). It is within the teachings of the present invention to utilize this current by opening tube 14 at an instant corresponding to t_4 and to supply an increment of current from tube 14 in order to build up the current in inductor 12 to its peak value. Such a result could be accomplished by making the natural frequency of the circuit 12, 19 approximately one-half of the natural frequency on which Fig. 2 is based, relative to the repetition rate of the control pulses. In such case the natural frequency of the oscillatory circuit would be such that the time required for one cycle of the oscillatory voltage plus the time required to build up maximum current in the plate inductance 12 would be equal to the reciprocal of the driving pulse frequency.

It will be understood that the curves of Fig. 2 represent simplified conditions, and while they take into consideration those factors bearing on the merits of the present invention, certain negligible factors are not reflected therein. For example, curve W is premised on the assumption that at instant t_2 , the moment of interruption of the current in inductor 12, the current immediately decreases along a sinusoidal characteristic. This assumption neglects the effect of the volt-

age which is built up across inductor 12 during the time that power tube 14 is conductive. As this voltage is very small compared to the transient oscillatory voltage (curve Z, Fig. 2), it is neglected herein for purposes of clarification.

While there has been shown and described what is at present considered to be the preferred embodiment of the present invention, it will be obvious to those skilled in the art that various modifications and substitutions of equivalents may be made therein without departing from the true scope of the invention as defined by the appended claims.

I claim:

1. A pulse-type power supply comprising an energy source, an inductance which is periodically given an increment of charge by that source, a source of substantially rectangular positive pulses and a switching tube controlled by said pulses and having said inductance as an anode load and its anode series-fed by said energy source, said tube periodically interrupting the flow of current in said inductance as the tube is rendered non-conductive at the termination of each pulse, thereby causing the magnetic field to begin to collapse, whereby there appears across said inductance an oscillatory voltage, means including an auto-transformer connected to said anode and utilizing said inductance as its primary for peak-rectifying said voltage to derive a unidirectional voltage, and capacitance effectively in parallel with said inductance to form a circuit resonating at a frequency F_2 equal to

$$\frac{nF_1}{1-F_1T}$$

in which n is an integer less than 4, F_1 is the repetition rate of the rectangular pulses, and T is the time during which the tube is conductive.

2. A pulse-type power supply comprising an energy source, an inductance which is periodically given an increment of charge by that source, a source of substantially rectangular pulses and a switching tube controlled by said pulses, said tube periodically interrupting the flow of current in said inductance as the tube is rendered non-conductive at the termination of each pulse, thereby causing the magnetic field to begin to collapse, whereby there appears across said inductance an oscillatory voltage, means for peak-rectifying said voltage to derive a unidirectional voltage, and capacitance effectively in parallel with said inductance to form a circuit resonating at a frequency F_2 equal to

$$\frac{nF_1}{1-F_1T}$$

in which n is an integer not more than 4, F_1 is the repetition rate of the rectangular pulses, and T is the time during which the tube is conductive.
